UNITED STATES PATENT OFFICE

ROBERT J. KOEPP, OF CHICAGO, ILLINOIS, ASSIGNOR TO THE CHENEY COMPANY, OF CHICAGO, ILLINOIS, A CORPORATION OF ILLINOIS

DESIGN FOR A COMBINED RADIO CABINET AND CLOCK

Application filed March 23, 1931. Serial No. 39,202. Term of patent 3½ years.

To all whom it may concern:

Be it known that I, ROBERT J. KOEPP, a citizen of the United States, residing in Chicago, in the county of Cook, State of Illinois, have invented a new, original, and ornamental Design for a Combined Radio Cabinet and Clock, of which the following is a specification, reference being had to the accompanying drawing, forming a part thereof, in which:

The drawing is a perspective frontal view of a combined radio cabinet and clock embodying my new design.

I claim:

The ornamental design for a combined radio cabinet and clock as shown.

ROBERT J. KOEPP.
